UNITED STATES PATENT OFFICE.

CHESTER T. DRAKE, OF CHICAGO, ILLINOIS.

DESIGN FOR A MIXER-BLADE.

SPECIFICATION forming part of Design No. 35,664, dated February 4, 1902.

Application filed December 3, 1901. Serial No. 84,579. Term of patent 14 years.

To all whom it may concern:

Be it known that I, CHESTER T. DRAKE, a citizen of the United States, and a resident of Chicago, Cook county, State of Illinois, have invented and produced a new and useful Design for a Mixer-Blade for Apparatus for Mixing Granular or Plastic Material—such, for instance, as cement, mortar, or concrete; and I do hereby declare that the following is a specification thereof, reference being had to the accompanying drawings, and to the reference characters marked thereon, and in which—

Figure 1 is a perspective view of a mixer-blade embodying my design looking toward the convex side A' thereof; Fig. 2, a perspective view of my design looking toward the concave side A² thereof, and Fig. 3 a plan view of my design.

The mixer-blade embodying my design illustrated in the accompanying drawings consists in a curved blade A, formed integrally with the hub B, from which it extends

in a diagonal direction with respect to the axis of the hub. 25

The blade A is of substantially uniform thickness and of a width equal to that of the hub B. A web a' extends between the convex surface A' of the blade and the outer surface of the adjacent side B' of the hub. 30

The hub B is provided with a rectangular opening b therethrough for receiving a rotatable shaft, to which the blade is adapted to be secured.

Having described my design, what I claim as new, and desire to secure by Letters Patent, is

The design for a mixer-blade as herein shown and described.

In witness whereof I have hereunto subscribed my name in the presence of two subscribing witnesses. 40

CHESTER T. DRAKE.

In presence of—

J. P. WIBORG,
GEO. L. WILKINSON.
